UNITED STATES PATENT OFFICE

132,119

DESIGN FOR A STOCKING OR SIMILAR ARTICLE

Jean L. Welch, West Reading, Pa., assignor to The Narrow Fabric Company, West Reading, Pa., a corporation of Pennsylvania

Application December 31, 1941, Serial No. 104,940

Term of patent 14 years

To all whom it may concern:

Be it known that I, Jean L. Welch, a citizen of the United States of America, residing at West Reading, in the county of Berks and State of Pennsylvania, have invented a new, original, and ornamental Design for a Stocking or Similar Article, of which the following is a specification, reference being had to the accompanying drawing, forming part thereof.

Figure 1 is a side view, on a reduced scale, of a stocking embodying my new design;

Fig. 2 is a view of the upper portion of the stocking fabric enlarged approximately one and one half times actual size, so that when this illustration is reduced to patent copy size the illustration will correspond in size approximately with the actual fabric.

I claim:

The ornamental design for a stocking or similar article, as shown and described.

JEAN L. WELCH.
